COMBINED WIG STAND AND COVER

Ana L. Douglas, 1302 E. Concord Ave.,
Orange, Calif. 92667

Filed Feb. 24, 1969, Ser. No. 15,879

Term of patent 14 years

Int. Cl. D20—02
U.S. Cl. D80—8

FIG. 1 is a perspective view of a combined wig stand and cover showing my new design;

FIG. 2 is a side elevational view thereof, the opposite side being a mirror image of the side shown;

FIG. 3 is a rear elevational view thereof; and

FIG. 4 is a top plan view thereof.

I claim:

The ornamental design for a combined wig stand and cover, substantially as shown and described.
